UNITED STATES PATENT OFFICE.

HANS M. ERICKSON, OF IRONWOOD, MICHIGAN, ASSIGNOR TO IRONWOOD MANUFACTURING COMPANY, OF IRONWOOD, MICHIGAN, A CORPORATION OF MICHIGAN.

MOP HOLDER.

Application filed February 13, 1928. Serial No. 254,062.

This invention relates to mops and is an improvement upon the mop disclosed in Patent #1,635,973, granted to Nikolai Hill, July 12, 1927.

5 An object of the invention is to improve and simplify the construction disclosed in the mentioned patent by providing improved means for securing the mop fabric in place, whereby the latter may be quickly and easily 10 removed and replaced and securely held in position, together with a novel form of mop fabric.

Another object of the invention is the provision of a buffer strip for the mop so as to 15 reduce danger of injury to furniture and woodwork, the construction of the mop frame providing convenient means for holding the strip.

With the above and other objects in view, 20 the invention further includes the following novel features and details of construction, to be hereinafter more fully described, illustrated in the accompanying drawings and pointed out in the appended claims.

25 In the drawings:—

Figure 1 is a plan view showing the mop frame and a portion of the handle, the jaws of the frame being closed.

Figure 2 is a like view with the jaws open.

30 Figure 3 is an enlarged fragmentary section on the line 3—3 of Figure 1.

Figure 4 is a like view on the line 4—4 of Figure 1.

Figure 5 is a detail view of the mop fabric.

35 Referring to the drawings in detail wherein like characters of reference denote corresponding parts, the mop as illustrated comprises a handle 10, a frame 11 and a mop fabric or mop cloth 12.

40 The frame 11 includes a bar which is formed of metal strips 13, the strips being riveted or otherwise secured together as shown at 14 and having clamped between them a buffer strip 15. This strip extends slightly beyond 45 the outer edge of the bar so as to provide a cushion or buffer and prevent injury to furniture and woodwork.

The metal strips 13 which form the bar each has extending rearwardly therefrom an extension 16 which is semi-circular in cross section so as to provide a socket 17 to receive the end of the handle 10, the latter being secured in place by means of a rivet or like fastening device 18.

55 The ends of the bar are curved as shown at

19 and these curved ends have hingedly secured thereto as shown at 20, the angular ends of jaws 21. The free ends of these jaws are provided with rightangular extensions 22 which are substantially semi-circular in cross section and which when the jaws 21 are closed as shown in Figure 1 of the drawings, engage over opposite sides of the handle 10, so that these extensions 22 provide a split sleeve through which the handle passes. Ex- 60 65 tending through the handle 10 is a pin 23 which is positioned to extend through slots 24 provided in the extensions 22 of the jaws. An annular member or ring 25 is provided and this ring is adapted to be removably positioned around the extensions 22 to hold the jaws in closed position, and in order to prevent accidental disengagement of the ring, the latter is provided with diametrically located notches 26, so that the ring may be slid along 70 75 the extensions 22 over the pin 23, whereupon a slight rotation of the ring will prevent the latter from leaving the extensions. The outer periphery of the ring may be provided with notches 27 so as to form a convenient 80 grip.

A mop fabric or cloth may be folded over the bar when the jaws are in open position and the latter may be then closed to engage and clamp the fabric or cloth in place. It 85 is preferred to use a mop fabric or cloth of the character illustrated in Figure 5 of the drawings. This mop fabric may be made of any suitable material and is provided with an opening 28 which receives the handle 10, 90 so that when the jaws 21 are open, this mop fabric may be slid along the handle and folded over the bar and the jaws afterward closed in the manner described. A strip 29 may be secured transversely of the mop 95 fabric.

The invention is susceptible of various changes in its form, proportions and minor details of construction and the right is herein reserved to make such changes as properly fall within the scope of the appended claims.

Having described the invention what is claimed is:—

1. A mop holder comprising a handle, a bar fixed to and extending transversely at one 105 end of the handle, a jaw hingedly secured to each end of the bar and capable of being moved to a closed position spaced from and parallel with the bar, means at the free ends of the jaws to engage the handle, and means 110

engageable with the handle engaging means of said jaws to secure the jaws in closed position.

2. A mop holder comprising a handle, a bar fixed to and extending transversely at one end of the handle, a jaw hingedly secured to each end of the bar and capable of being moved to a closed position spaced from and parallel with the bar, means at the free ends 10 of the jaws to engage the handle, means engageable with the handle engaging means of said jaws to secure the jaws in closed position and means carried by the handle for engagement with the jaw securing means to hold the latter in position.

3. A mop holder comprising a handle, a bar fixed to and extending transversely at

one end of the handle, a jaw hingedly secured to each end of the bar and capable of being moved to a closed position spaced from and 20 parallel with the bar, right angularly disposed extensions of substantially semi-circular cross section at the free ends of the jaws to engage upon opposite sides of the handle when the jaws are in closed position, said extensions having elongated slots therein, a pin extending through the handle for passage through the slots, and an annular member 25 removably positioned around the extensions of the jaws and engaging the pin to hold the 30 jaws in closed position.

In testimony whereof I affix my signature,

HANS M. ERICKSON.
